(57) **CLAIM**

The ornamental design for a shoe, as shown and described.

DESCRIPTION

The present application is related to a co-pending design application with the title "Shoe", an application Ser. No. 29/679,354, and filed on Feb. 5, 2019 and is related to a second co-pending design application filed on the same date as the present application by inventor Marvin Williams with the title "Shoe", both of which applications are incorporated by reference herein in their entirety.

FIG. 1 is a top, left, and front perspective view of an ornamental design for a shoe;

FIG. 2 is a front elevational view of the shoe of FIG. 1;

FIG. 3 is a rear elevational view of the shoe of FIG. 1;

FIG. 4 is a left side elevational view of the shoe of FIG. 1;

FIG. 5 is a right side elevational view of the shoe of FIG. 1;

FIG. 6 is a top plan view of the shoe of FIG. 1;

FIG. 7 is a bottom plan view of the shoe of FIG. 1; and,

FIG. 8 is a bottom, right, and rear perspective view of the shoe of FIG. 1.

The dash-dash-dash lines are included for the purpose of illustrating portions of the shoe that form no part of the claimed design.

1 Claim, 7 Drawing Sheets
